UNITED STATES PATENT OFFICE.

FRANZ KOMNICK, OF ELBING, GERMANY.

DEVICE FOR INTERMITTENTLY ROTATING TABLES OF MACHINE-TOOLS.

SPECIFICATION forming part of Letters Patent No. 746,849, dated December 15, 1903.

Application filed June 29, 1903. Serial No. 163,632. (No model.)

To all whom it may concern:

Be it known that I, FRANZ KOMNICK, a subject of the Emperor of Germany, and a resident of Elbing, Germany, have invented a certain new and Improved Device for Intermittently Rotating the Tables of Machine-Tools, of which the following is a full, clear, and exact description.

The present invention consists of an improved device for intermittently rotating the tables of machine-tools and the like, and comprises the details of construction hereinafter set forth, and particularly pointed out in the claims.

15 In order to render the present specification easily intelligible, reference is had to the accompanying drawings, in which similar letters of reference denote similar parts throughout the several views.

20 Figure 1 is an elevation of the device; Fig. 2, a plan of the same; Fig. 3, a plan and side elevation of one of the tooth-segments, and Fig. 4 a vertical cross-section through the vertically-disposed segment.

25 The table *e* is mounted to rotate around its vertical axis, and the rotation is effected by a horizontally-located tooth-segment *d*, adapted to rock on substantially the same vertical axis as the table, and by a second tooth-segment *c*, having teeth *z*, meshing with the said horizontally-disposed segment *d*. The segment *c* is adapted to rock on a horizontally-disposed pivot *c'* by means of a crank-disk *b*, mounted on a rotary shaft *o*, the crank-pin of said disk

35 being coupled to a suitable point of the segment *c* by means of the connecting-rod *a*. The horizontally-disposed segment *d* may either be adapted to rock on the vertical axis of the table *e* or it may be guided on the rim 40 or guideway *i*, Fig. 4, of the table, and the table is provided with ratchet-recesses *k*, in which a pawl *h* engages by the pressure of a spring *g*. In the drawings the segment *d* is shown guided in the guideway *i* of the table-45 rim by means of the guide-blocks *f*, secured to the said segment.

The operation of the device is very simple. When the shaft *o* is rotated, the vertically-disposed segment *c* will be rocked by the connecting-rod *a* and will correspondingly rock the segment *d*. The pawl *h* of this segment will engage a ratchet notch or recess *k* of the table *e* and turn the same as far as the segment is rocked. The segment *c*, and with it *d*, now be-

gin their return movement, during which the 55 pawl *h* will slide over the smooth rim of the table, allowing the same to remain in the position into which it was turned on the forward stroke of the segment.

It will be obvious from the foregoing description that by reversing the direction of the pawl *h* and providing notches having their ratchet-surface in the opposite direction to those illustrated the direction of stepwise rotation of the table could be reversed, while 65 the shaft *o* would still rotate in the same direction.

By means of the present invention the stepwise movement of the table round a much larger angle is attained than has hitherto 70 been the case by the ratchet movements hitherto employed.

I claim as my invention—

1. In an intermittent grip device, in combination, a table, a vertically-disposed tooth-75 segment and means for rocking the same, a horizontally-disposed segment in engagement with the same, and means for coupling the said horizontally-disposed segment to the table on its movement in one direction of its recipro-80 cipation substantially as described.

2. In an intermittent grip device, in combination, a table, a vertically-disposed tooth-85 segment and means for rocking the same, a horizontally-disposed segment in mesh with the same and having a spring-pressed pawl mounted thereon, there being ratchet-recesses in the rim of the table in which said pawl engages during its movement in one direction of its reciprocation substantially as 90 described.

3. In an intermittent grip device, in combination, a table, a vertically-disposed tooth-95 segment and a horizontally-disposed segment in mesh with the same, means for rocking the vertically-disposed segment and means for guiding the horizontally-disposed segment on the rim of the table, means for coupling the horizontally-disposed segment to the table during one beat of its reciprocation substan-100 tially as described.

In witness whereof I have hereunto set my hand in presence of two witnesses.

FRANZ KOMNICK.
